SAFETY RAZOR BLADE

Samuel C. Stampleman, Cohasset, Mass., assignor
to Gillette Safety Razor Company, Boston,
Mass., a corporation of Delaware

Application November 9, 1944, Serial No. 562,605

1 Claim. (Cl. 30—346)

This invention relates to blades for safety razors and more particularly to improvements in blades of the thin, flexible type.

Heretofore, the cutting edges of razor blades have been formed with the oppositely disposed bevels, which produce the edges, commencing directly and immediately from the opposed surfaces of the body portion of the blade and from lines quite close to the edges to be formed. Such construction makes for rigidity of the cutting edge when the blade is clamped between the cap and guard of the razor.

It has been found that the shaving qualities of a blade are considerably improved if its cutting edge is flexibly supported so that as it approaches the beard to make its severing contact therewith a slight yielding action occurs; that is, if the cutting edge is arranged so that it will flex minutely, a smooth, cleaner severing action takes place upon the follow-through of the stroke. This is mechanical compensation for the skilled wrist-flex action of practiced barbers. While the support for the cutting edge must be sufficiently pliant to permit of the slight flexing beforementioned it still must have sufficient body to prevent the edge from chattering.

Accordingly, it is the object of the present invention to provide a razor blade having cutting edges, the cross-sectional outline of which are, in miniature, substantially that of the old-fashioned barber's razor, and which cutting edges are partially oriented from the blade proper by oppositely disposed grooves extending longitudinally in the opposite surfaces of the blade, adjacent the edges, to form slightly resilient connecting webs between the cutting edge portions and the blade proper.

These and other features of the invention will be best understood and appreciated from the following description of two preferred embodiments thereof, selected for purposes of illustration and shown in the accompanying drawing in which:

Fig. 1 is a perspective view of the blade on an enlarged scale;

Fig. 2 is a cross-sectional view, taken on the line II—II of Fig. 1;

Fig. 3 is a fragmentary sectional elevation showing the blade as flexed between guard and cap members of a safety razor; and

Fig. 4 is a similar view but showing a modification of the longitudinal edge-orienting grooves, the grooves herein being wider and extending under the cap member of the razor.

The invention as herein shown is embodied in a blade of the well-known "Gillette" type but it

is not restricted in its application to that or to any particular type of blade and with suitable modifications may be incorporated in any blade having a fairly substantial thickness, say in the order of .006 of an inch or more.

The blade herein shown is generally rectangular in outline, having reentrant corner recesses which define elongated unsharpened end portions 10 and 11, between which extend two similar side portions 12 and 13 that are separated throughout their length by a medial slot 14. The blade is of uniform thickness throughout its body portion and is flexible transversely of its medial longitudinal center. The slot 14 is of the usual configuration found in "Gillette" blades, being substantially co-extensive in length with the cutting edges 15 of the blade, and having a centrally disposed circular enlargement and other intermediate enlargements that cooperate with corresponding projections (not shown) on either the cap or the guard of the razor for securely and accurately locating the blade thereon.

The outer longitudinal edges 15 of side portions 12 and 13 are ground, honed and stropped to present keen, parallel shaving edges.

Preferably just prior to the edge-grinding operations, oppositely disposed rectangular shaped grooves 16 having sharply defined base corners are ground throughout the entire length of the side portions 12 and 13, adjacent the edges 15. The depth to which the grooves are cut is governed conformably to the thickness of the blade but in any event sufficient stock is removed from both surfaces to form a thin, flexible web 17 of uniform thickness throughout its entire length and width. The thickness of the web 17 approximates 50 per cent but not greater than 60 per cent of the thickness of the blade stock. Specifically, in a blade of .006" thickness, the grooves are formed to a depth in the order of .0015" in opposite surfaces of the blade adjacent each edge 15. The width of the grooves is preferably substantially greater than their depth, say, at a minimum in the order of .012", although, as shown in Fig. 4, the width may be substantially increased and thereby corresponding increased flexibility of the rib 17 obtained.

These grooves, by virtue of the sharply defined corners, partially but substantially orient the cutting edges from the blade proper. Finally, upon the edge-grinding operations being performed as above outlined, the sectional outline of the cutting edge, in miniature, substantially approximates the sectional outline of the old-fashioned barber's razor; that is, the abrupt termination of the

bevels at that point where they are intersected by the vertical walls of the grooves 16 nearest the cutting edge correspond to the back of the old-fashioned razor. From this "back," which is the full thickness of the blade body, the bevels taper toward the front or cutting edge and by this formation the greatest weight of the portion forming the cutting edge lies immediately adjacent the yielding web 17. The fulcrum of web 17 about which the cutting edge 15 flexes, lies somewhere between the medial longitudinal centre of the web and the perpendicular wall of the groove that is farthest away from the cutting edge, and thus a flexible support for a relatively inflexible cutting edge is provided.

An alternative method of providing the groove 16 in the blade is by swaging the stock from opposite sides with suitably formed swaging tools. In practicing this method, the grooving operation is performed concurrently with the blade-outlining or blanking operation and before the tempering process has taken place. In using this method any over-extension of the width of the blade between its parallel cutting edges is corrected by removal of the excess stock during the edge-grinding operations.

The location of grooves 16 on the blade is such that when the narrower form of groove is provided (see Fig. 3) it lies completely beyond the outer edge of the cap 18 of the razor when the 30 blade is clamped between the cap and the fulcrum shoulder 19 of the guard. When the wider

groove, shown in Fig. 4, is provided, a portion thereof lies under the cap for approximately three-fourths or thereabouts of the groove width. In this latter form, wherein the degree of flexibility of the cutting edge is materially increased by the wider web 17, the extreme outer edge of the cap acts as a limiting stop for the outward flex of the cutting edge by the base of the upper groove 16 contacting the lower corner of the cap when the outward flex of the cutting edge has exceeded a proper amount of yield and would, if not prevented, increase the exposure of the cutting edge beyond safe limits.

Having thus disclosed my invention and described in detail illustrative embodiments thereof, I claim as new and desire to secure by Letters Patent:

An improved safety razor blade having a flexible body of uniform thickness throughout, a relatively inflexible beveled cutting edge portion, and a thin flexible web co-extensive in length with the cutting edge, connecting the cutting edge portion and the body of the blade and being of substantially less thickness than the body of the blade, the back of the cutting edge portion being the full thickness of the body of the blade and the blade being constructed and arranged to be clamped in shaving position with the said connecting web free to flex and to support the relatively inflexible cutting edge portion in a yielding resilient manner in shaving position.

SAMUEL C. STAMPLEMAN.
